PROJECTILE WITH A DELAYED EXPLOSION
Robert B. Young, Greenbelt, Md., assignor to the United States of America as represented by the Secretary of the Air Force

Filed Nov. 29, 1966, Ser. No. 597,821
3 Claims. (Cl. 102—4)

ABSTRACT OF THE DISCLOSURE

A projectile is disclosed in which the explosion is delayed in an improved predetermined manner. The projectile is fired from a casing which contains the projectile and a propellant. The projectile is formed with a central hole or core for tightly receiving a burst tube. The ends of the latter are closed except for an opening which slidably receives one end of a centrally located rod. The other end of the rod is anchored in the casing. The tube contains an explosive charge. The length of the rod is predetermined to give the required time delay in exploding the projectile by uncovering the opening in the tube as the projectile moves along the casing, thus allowing the gases from the propellant to reach the explosive charge in the tube to cause an explosion of the projectile.

When launching a missile from an aircraft it is necessary that the missile or projectile be exploded, not only at a designated point in space in order to hit the target, but also at a minimum safe distance from the point of delivery of the missile. Strict control of the time of explosion after delivery therefore is imperative. This requirement is difficult to attain, especially in the case of close targets on account of extreme shortness of time that might be available between the ignition of the full propellant charge and the explosion of the missile.

Moreover, even in the case of distant targets, fuses of the cord type, when used to ignite the propellant of a missile, are not altogether predictable as to rate of burn. Some control might be exercised by regulating the character and quantity of the propellant but this expedient is not sufficiently critical and definite in pinpointing where the explosion will take place.

Other forms of controlled initiation of the igniting devices have been proposed, such as the pyrotechnic delay fuzes operated by a hot wire, also the mechanical escape-ment form of fuzes which rely on the amount of acceleration of the projectile. However, these fuzes are complicated from the mechanical standpoint, and are quite expensive. Some of them are overly sensitive to high acceleration and very few, if any, give the high degree of control of the time and place of the explosion that is necessary, particularly when using a projectile which propagates the ignition through the propellant at a fast rate and the target is close.

An object of the invention is to provide an improved fuzing means for igniting the propellant and exploding a projectile propelled or dropped from aircraft.

Another object is to provide a grenade fuze of inexpensive character which can be adjusted to give any regulated amount of delay between the complete ignition of the propellant and the bursting of the projectile.

These objects are attained in brief by providing a central bursting tube within the projectile and timing the bursting period by permitting the heated propellant gases to enter and explode the tube at a predetermined time after the propellant has been ignited.

While the invention has application to the propelling of a missile or projectile out of a gun, I have shown, as a typical use, the operation of the improved fuzing structure in connection with aircraft delivery of the projectile.

2

The invention will be better understood when reference is made to the following description and the accompanying drawings.

FIG. 1 represents a longitudinal sectional view of a missile including the improved explosion-delay-feature constituting the subject of the present invention;

FIG. 2 is an end view of the missile looking upwardly from about the position of the line 2—2 in FIG. 1; and

FIG. 3 shows the relative position of the parts of the improved grenade fuze just prior to the explosion of the projectile.

Referring to FIG. 1, reference character 1 represents a cylindrical casing of iron, open at the lower end and provided at its upper end with a heavy transverse wall 2 which has a central threaded opening. The latter merges into an extended opening 4, passing through the entire thickness of the wall.

A grenade fuze 5, shown in outline, and may be of any suitable and well-known type, is secured to the upper flat surface of the wall 2. The lower end of the grenade fuze is provided with a threaded extension 6 which engages the threads of the central opening. This extension is hollow and has a depending rod 7, also hollow, extending through the opening 4. The interior of the threaded extension and the rod 7 are in communication with the charge in the interior of the grenade fuze. The latter has the usual safety pin 8, a spring-operated lever, a striking pin and primer, also an igniting charge, all of which are known in the art and therefore need not be described.

When the charge is ignited in the manner explained hereinafter, the heated products of combustion from the grenade fuze are forced downwardly through the passageway into the compartment 9 from within the casing and positioned directly below. The compartment contains a relatively long and stiff fuze rod 10, preferably made of a refractory metal, which extends along the central axis of the compartment. This rod is anchored at one end in the wall 2 and for this purpose may terminate in a branched portion 11, the legs of which enter the metal of the wall. Thus the rod cannot obstruct the end of the passageway. The purpose of the rod will be described presently.

Surrounding the rod 10 and positioned somewhat remote from the wall 2, there is a tube 12 of relatively thin steel, threaded for a short distance at each end. A metal plug 13 is threaded into the tube at the ends thereof, this plug having a countersunk central portion 14 and an aperture in the center (not shown) to provide a sliding fit for the rod 10. A Teflon plug (not shown) having a press fit hole may be employed in the countersunk portion to accommodate the fuze rod. The plug prevents the entrance of gas, either hot or cold, yet allowing forced movement of the rod lengthwise of the tube. The latter is surrounded by a projectile 15 which has a central opening that snugly receives the tube 12. The projectile has an outside diameter slightly less than the interior diameter of the casing 1 so as to minimize friction as it moves through the casing. As indicated, the rod 10 may extend any desired distance beyond the lower end of the tube 12 since it is supported at two points along the central axis by the tube 12, which in turn, is snugly contained within the projectile 15. The latter may be of any suitable type which can be exploded by an internal blast.

The compartment 9 is filled with a propellant of any suitable and well-known type before the projectile is introduced into the casing. The tube 12 is also filled with an explosive charge by unscrewing one of the end plugs.

While various ways may be employed to place the bomb structure into a horizontal or vertical trajectory, the most effective manner would be to drop the structure

from a plane over the target area. A delayed-opening parachute could advantageously be connected to the safety pin 8. The latter would remain in place as long as the parachute remains undeployed; but when the parachute opens at the set altitude, the resulting tug on the shroud lines would cause the pin to be withdrawn. This effect is diagrammatically shown in FIG. 3 in which the parachute is designated 17. The latter need be relatively small since its function is only to pull the pin and not to support the bomb. The propellant in the grenade fuze will have been caused to ignite and produce highly heated gas which flows downwardly into the compartment 9 so as to set off the propellant charge.

The resulting gas from the propellant will move the projectile 15 and the contained tube 12 with respect to the casing. Tube 12 will therefore slide along the fixed fuze rod 10. Eventually the tube will have reached a position such that the upper end of the tube will have cleared the lower end of the rod 10.

Inasmuch as the fuze rod 10 will now have been completely withdrawn from the central tube as indicated in FIG. 3, heated gases indicated at 16 can now readily flow through the upper end opening in the tube to ignite the explosive material therein. The result is that the tube 12 is caused to burst and this will immediately explode the projectile 15.

It is apparent that the time taken for the expanding propellant gases to reach the interior of the burst tube 12 through its end opening will depend upon the time taken for the remote end of the fuze rod to clear the opening as the projectile and tube move together through the casing. Thus, the length of the rod becomes a ready means for controlling the delay of any calculated amount between the time that the fuze in the grenade is ignited until the projectile is exploded.

The rod 10 may have any length desired, long or short, since it is well supported within the burst tube 12 either by the plugs 13 and/or by the surrounding explosive material and the tube is in turn firmly supported within the projectile.

It is evident that the use of the improved fuze rod and surrounding tube as an explosion relay device can be used with gun-fired projectiles to advantage on account of the extreme accuracy with which the length of the fuze rod and the resulting time delay can be calculated and duplicated.

While a specific embodiment has been described, it is obvious that numerous changes may be made without departing from the general principles and scope of the invention.

I claim:

1. In apparatus for exploding a projectile, the combination of a casing closed at one end and loosely surrounding the projectile, a propellant between the closed end of the casing and the adjacent end of the projectile, a rod extending rectilinearly through the casing and secured at one end to the closed end of the casing, said projectile having a central opening, a tube tightly fitted within the opening, plug means closing the ends of said tube, each of said plug means having an opening which slidably receives the free end of said rod whereby the rod extends through said tube, and an explosive charge between the rod and the tube.
2. The combination as set forth in claim 1 and in which said rod is of such length that when the projectile is moved through the casing by said propellant, the opening in the tube is uncovered to permit the explosive charge in the tube to be ignited by the propellant gases, thereby to explode the projectile.
3. The combination as set forth in claim 2, and in which said rod is substantially of the same length as the length of the casing.
